FOLDING BATHROOM STOOL

Manly S. Mumford, Evanston, and Eugene H. Cowles, Chicago, Ill.; said Cowles assignor to said Mumford

Application May 9, 1947, Serial No. 747,044

10 Claims. (Cl. 155—151)

1

The present invention relates to a folding bathroom stool which is adapted to be set directly in a shower stall or in a bath tub. There are innumerable occasions when a small stool is very advantageous when taking a shower in a shower stall, or under a shower attachment extending over a bath tub, or even when taking a tub bath in a conventional bath tub. For example, when a person is shampooing his hair or washing his feet under a shower, it is much safer and more comfortable to do these operations in a sitting position. All operations performed in a standing position under a shower are always subject to a very real risk, because of the danger of slipping on a cake of soap or on the wet surface of the tub or shower stall.

Our improved bathroom stool has been particularly designed to meet the above situations. The stool is composed of a material which will not be adversely affected by continued subjection to water, this material preferably consisting of aluminum or an aluminum alloy. The stool has specially constructed rubber feet which prevent it from slipping on the bottom of the tub or on the floor of the shower stall. Also, the stool has the proper width and other dimensions to enable it to be used safely and comfortably in a narrow shower stall, or resting on the relatively narrow bottom of a bath tub.

One of the particular objects of the invention is to provide an intermediate supporting member disposed below the top seating surface which performs the different functions of a foot rest, shelf, step, and folding strut for spacing the folding legs of the stool. In the operative position of the stool, the forward portion of this intermediate supporting member projects forwardly beyond the front edge of the top seating surface and the rearward portion extends back in under said top seat. When using the stool in a shower stall or tub, the forwardly projecting portion of this intermediate support can be used as a foot rest to support either foot in a raised position convenient for washing. At the same time, the rearwardly extending portion which extends back in under the top seat can be used as a shelf for holding soap, liquid shampoo, or any other articles where they will not be subjected to the direct spray of the shower.

Another particular object of the invention is to provide an improved folding construction which will enable this bathroom stool to be collapsed into a relatively small flat unit when not in use. One of the particular features of this folding con-

struction is the arrangement whereby the legs are pivotally connected with the seat for sidewise folding motion and the intermediate support is pivotally connected with the seat for fore and aft folding motion. When the legs are swung downwardly and laterally to their normal supporting positions, the intermediate support can then be swung downwardly and forwardly to occupy a position between the right and left legs, so as to function as a horizontal spacing strut to lock the legs in their normal positions. When the intermediate support is in this position of a horizontal spacing strut, it can also be used as an intermediate step in any situation where the device is being used as a step stool or low step ladder.

Other objects, features and advantages of the invention will appear from the following detailed description of one preferred embodiment thereof.

In the accompanying drawings illustrating such embodiment:

Figure 1 is a plan view looking down upon our improved bathroom stool showing the leg structures and intermediate support in their unfolded or normal positions;

Figure 2 is a front elevational view of the stool with the leg structures and intermediate support in their normal positions;

Figure 3 is a side view of Figures 1 and 2;

Figure 4 shows the stool folded into its collapsed position, this view corresponding to the front view of Figure 2;

Figure 5 is a detail sectional view taken approximately on the plane of the line 5—5 of Figure 3 showing the manner in which the rear edge of the intermediate supporting member is pivotally carried on swinging suspension links;

Figure 6 is a sectional view taken approximately on the plane of the line 6—6 of Figure 3 showing the manner in which the upper ends of these suspension links are pivotally connected with the top seat;

Figure 7 is a detail sectional view taken approximately on the plane of the line 7—7 of Figure 3 showing the interlocking supporting brackets which join the leg structures with the intermediate supporting member; and

Figure 8 is a detail sectional view taken approximately on the plane of the line 8—8 of Figure 7.

The top seat 10 upon which the user is to sit is preferably constructed in the form of a rectangular sheet-metal pan punched out to have a downwardly extending flange or lip 11 extend-

ing around all four sides thereof to stiffen the pan. This pan is preferably composed of a soft aluminum adapted to be heat treated after forming, but it will be understood that other metals or other alloys may be employed so long as they are not adversely affected by continued subjection to the shower spray. The central portion of this seat is provided with a plurality of drain holes 12 (Figure 1) for draining any water tending to accumulate thereon. The central portion of the seat is preferably depressed toward these drain holes, so that any standing water will have a downward slope toward these holes.

The seat 10 is supported on right and left pairs of legs the right pair of legs being integrally joined together as a right leg structure 14, and the left pair of legs being integrally joined together as a left leg structure 15. These leg structures are preferably constructed as sheet-metal stampings, composed of soft aluminum or the same metal or alloy as the seat pan 10. As shown in Figure 3, each of these leg structures is of oblique A-shape having the front legs 14a-15a sloping forwardly at a considerable angle and having the rear legs 14b-15b extending substantially vertically. The front and rear leg portions of each leg frame are joined by a top cross bar portion 14c-15c and by an intermediate cross bar portion 14d-15d. These two leg frames 14 and 15 are formed with marginal stiffening flanges 14' and 15' extending around the margins of the front and rear legs and the upper and intermediate cross bar portions. These right and left leg frames can be made as identical counterparts, except for the hinge lugs which will now be described.

Referring to Figures 1 and 2, the right leg structure 14 has front and rear hinge lugs 16, 16' projecting inwardly from the top edge of the leg structure. These hinge lugs have pivotal mounting on aligned front and rear hinge pins 17, 17' which are mounted in hinge eyes in the depending marginal flange 11 at the front and rear edges of the seat pan 10. Thus, when the stool is to be folded, the right leg structure 14 can be swung inwardly and upwardly to a collapsed position disposed substantially parallel to and in close proximity to the under side of the seat 10. When the leg structure is swung down to its vertical operative position the top edge of the leg structure and its marginal flange 14' form an abutment adapted to abut the under side of the seat 10 for preventing the leg structure from swinging outwardly beyond the substantially vertical position shown in Figure 2. The left leg structure 15 has a similar pair of front and rear hinge lugs 18, 18' having pivotal mounting on front and rear aligned hinge pins 19, 19' carried in pivot eyes in the depending marginal flange 11 at the front and rear edges of the seat. The hinge lugs for the left leg structure are of longer length than the hinge lugs for the right leg structure, so that when the left leg structure is swung upwardly to a folded position it will overlie the right leg structure, as shown in Figure 4. Also, when this left leg structure 15 is swung down to its vertical operative position, the top edge of the leg structure and its marginal flange 15' form an abutment adapted to abut the under side of the seat 10 for preventing the leg structure from swinging outwardly beyond the substantially vertical position shown in Figure 2.

The front and rear legs of each hinged leg structure are provided with a unique construction of rubber feet 21 and 22 (Figure 3) which mini-

mize the possibility of the stool slipping on a wet surface. These rubber feet each consist of an upper channel-shaped section 23 adapted to fit up over the inner and outer sides of the main web or wall of each supporting leg. Each channel-shaped section is adapted to be fastened to said main web portion by transverse rivets 24 composed of aluminum or other rust-proof material. The bottom surfaces of these rubber feet have a transversely slotted or ribbed formation 25 which increase the gripping action of the rubber feet on a wet surface, somewhat comparable to the action of a new tire tread on a wet pavement. By reason of the outward slope of the front leg 14a of right hand leg frame 14, the front rubber foot 21 stays entirely clear of the pivot lug 18 of left hand leg structure 15 when the right hand leg structure is swung upwardly to its inner folded position lying between the seat and the left hand leg structure. In this same regard, the rear foot 22 of leg 14b clears the hinge lug 18' by staying forwardly thereof when the leg structure 14 is swung up to its folded position.

Referring now to the intermediate supporting member which performs the different functions of a foot rest, shelf, step and folding strut, this member is indicated at 30 and is preferably constructed as a sheet-metal stamping, preferably composed of soft aluminum, and having the form of a shallow rectangular pan stiffened by a downwardly extending marginal flange 31 formed around all four sides thereof. The central portion of this pan is also provided with drain holes 32, similar to the drain holes 12 of the seat 10, and said central portion is preferably depressed toward these drain holes, so that standing water will have downward slope toward the holes. The rear edge of the intermediate support 30 has a swinging suspension link mounting, best shown in Figures 5 and 6. Two identical links 34 have their lower ends pivotally connected with the right and left sides of the intermediate support 30 at points adjacent to the rear edge thereof (Figure 3). These links are also preferably composed of aluminum. The pivotal connections preferably comprise clevis pins or shouldered pivot pins 35 which pass through pivot apertures in the lower ends of the links 34 and through apertures in the flanges 31 of the pan 30. The reduced inner ends of these pivot pins are headed over after insertion through the holes in the flange 31. Aluminum washers 38 are preferably mounted on the intermediate portion of the pivot pins to each side of the link 34.

The upper ends of the links have a similar pivot mounting on pivot brackets 40 which are welded or riveted to the under side of the seat pan 10 at points best shown in Figures 1 and 3. The marginal flanges 14' and 15' at the tops of the leg frames are notched out to clear these brackets 40, as shown in Figure 1. The pivotal connection between the links 34 and the pivot brackets 40 is by a similar construction and arrangement of shouldered clevis pins 35', preferably composed of aluminum and carrying aluminum washers 38' on opposite sides of the links. When the support pan 30 is swung up to its folded position substantially against the under side of the seat pan 10, the support pan 30 swings upwardly between the suspension links 34 and the latter swing upwardly into positions disposed parallel with the outer edges of the support pan.

When the intermediate support 30 is in its lower operative position, the front edge portion

thereof is mounted in front support brackets 42 which are secured to the sloping front leg portions 14a and 15a of the two leg frames. As best shown in Figure 7, each of these support brackets is formed with an attaching plate portion 43 which is adapted to be welded or riveted to the back surface of the stiffening flange 14' or 15' of its respective leg frame 14 or 15. Extending downwardly from this attaching plate portion is a U-shaped portion 45 which forms an interlocking socket adapted to receive the downwardly extending flange 31 of the support pan 30 adjacent the front edge of said pan. Extending transversely through this U-shaped portion 45, adjacent the bottom thereof, is a rivet 46 adapted to function as a stop or locking pin. As shown in Figure 8, the lower edge of the flange 31 is formed with a notch 48 adapted to drop down over rivet 46 when the forward edge of the side flange 31 is in resting position in the U-shaped support 45. This pin and notch arrangement prevents fore and aft sliding of the front edge of the support pan within the support sockets 45.

It will be seen from Figure 3 that when this intermediate support 30 is in its normal operative position, the forwardly projecting portion of the support extends sufficiently beyond the front edge of the seat 10 that it can be used as a foot rest to support either foot in a raised position convenient for washing. It will also be seen from Figure 3 that the rearwardly extending portion of the member 30 extends back in under the top seat 10 where it can be used as a shelf for holding soap, liquid shampoo, or any other articles in a relatively protected position where they will not be subjected to the direct spray of the shower. Furthermore, this intermediate support 30 can be used as an intermediate step in any situation where the device is being used as a step stool or low step ladder. Finally, this intermediate support 30 functions as a spacing strut for positively locking the leg frames 14 and 15 in their downwardly extending operative positions. This positive locking prevents any accidental inward folding of the leg frames, and the engagement of the flanges 31 within the U-shaped sockets 45 also interlocks the leg frames against outward folding movement. When the device is to be collapsed into its folded position, the front edge of the intermediate support pan 30 is merely lifted upwardly sufficiently far to clear the side flange portions 31 from the U-shaped front support sockets 45, whereupon this support pan is then swung rearwardly and upwardly to place the support pan in a nested position substantially in contact against the under side of the top seat 10. Following this, the right hand leg frame 14 is then swung upwardly to its folded position, after which the left hand leg frame 15 is swung upwardly to its folded position overlying the right hand leg frame. Figure 4 shows the parts in their respective folded positions, from which it will be seen that the device folds into a very small space. By constructing all of the main parts of non-corrosive metals, such as aluminum or magnesium or any of their alloys, the device will not deteriorate or corrode from repeated subjection to hot or cold water, or continued standing in water. The aluminum construction also makes the device very light in weight. As illustrative of typical dimensions, particularly adapted to use in an average size bath tub, one preferred embodiment of our invention has a seat pan approximately 20 inches wide and 8.5 inches deep, and has leg structures folding out to a separa-

tion of approximately 18 inches, these leg structures supporting the seat about 15.5 inches high. However, our invention is not limited to these dimensions.

While we have illustrated and described what we regard to be the preferred embodiment of our invention, nevertheless it will be understood that such is merely exemplary and that numerous modifications and rearrangements may be made therein without departing from the essence of the invention.

We claim:

1. In a device of the class described, the combination of a seat portion, right and left leg structures pivotally connected with said seat portion for sidewise folding movement into positions substantially parallel with the under side of said seat portion, an intermediate step, and mechanism movably connecting said intermediate step with said seat portion including swinging links pivotally connected to said intermediate step and to said seat portion whereby said intermediate step can serve as a horizontal spacing strut between said pivoted leg structures when the latter are in their operative positions, and whereby said intermediate step can be swung upwardly into a folded position substantially against the under side of said seat portion when said leg structures are to be swung up into their folded positions.

2. In a device of the class described, the combination of a top seat portion, right and left leg structures each comprising integrally joined front and rear legs, means pivotally connecting said leg structures with said seat portions for sidewise folding movement into positions substantially parallel with the under side of said seat portion, an intermediate step below said seat portion normally disposed with a front edge projecting outwardly beyond the front edge of said seat portion

whereby said intermediate step can serve as a raised foot support, and means movably connecting said intermediate step with said seat portion whereby said step can be moved rearwardly and upwardly to a folded position adjacent the under side of said seat portion when said leg structures are swung upwardly into their folded positions.

3. In a device of the class described, the combination of a top seat portion, right and left leg structures each comprising integrally joined front and rear legs, means pivotally connecting said right and left leg structures with the under side of said top seat portion along fore and aft hinge axes whereby said leg structures can be folded upwardly into positions substantially parallel with the under side of said seat portion, an intermediate step normally spaced below said seat portion, suspension links pivotally connecting the rear portion of said intermediate step with the under side of said seat portion, and supporting brackets on said leg structures for supporting the forward portion of said intermediate step, whereby said intermediate step can be swung rearwardly and upwardly to a folded position adjacent the under side of said seat portion when said leg structures are to be swung upwardly to their folded positions.

4. In a device of the class described, the combination of a top seat portion, leg structures pivotally connected with said seat portion for folding movement into positions substantially parallel with the under side of said seat portion, an intermediate support, suspension links pivotally connecting the rear portion of said intermediate support with the under side of said seat portion, U-shaped supporting brackets secured to said leg

7
structures for supporting the front portion of said intermediate support, and cooperating locking surfaces on said U-shaped supporting brackets and on said intermediate support for normally holding said intermediate support against fore and aft movement.

5. In a folding bathroom stool, the combination of a seat portion, leg structures pivotally connected with said seat portion for sidewise folding movement into positions substantially parallel with the under side of said seat portion, an intermediate step, and means movably connecting said intermediate step with said seat portion for fore and aft folding movement into a position adjacent to the under side of said seat portion.

6. In a folding bathroom stool, the combination of a sheet-metal seat portion, sheet-metal leg structures pivotally connected with said seat portion for sidewise folding movement into positions substantially parallel with the under side of said seat portion, a sheet-metal intermediate step, and means movably connecting said intermediate step with said seat portion for fore and aft folding movement into a position closely adjacent the under side of said seat portion.

7. In a folding bathroom stool, the combination of a seat portion composed of a sheet aluminum stamping, leg structures composed of sheet aluminum stampings pivotally connected with said seat portion for sidewise folding movement into positions substantially parallel with the under side of said seat portion, an intermediate step composed of a sheet aluminum stamping, means pivotally connecting said intermediate step with said seat portion for fore and aft folding movement into a position closely adjacent the under side of said seat portion, and rubber feet on said leg structures having non-skid lower surfaces adapted to minimize the possibility of slipping on a wet surface.

8. In a folding bathroom stool, the combination of a seat portion, folding leg structures pivotally connected with said seat portion for folding movement into positions substantially parallel with the under side of said seat portion, a folding intermediate support, means movably connecting said intermediate support with said seat portion for folding movement toward and away from said seat portion, and interlocking means for interlocking said intermediate support to said leg structures when the latter are in their operative positions,

8
whereby said intermediate support interlocks said leg structures against accidental inward or outward folding motion.

9. In a folding bathroom stool, the combination of a seat portion, folding leg structures pivotally connected with said seat portion for folding movement into positions substantially parallel with the under side of said seat portion, a folding intermediate support, means movably connecting said intermediate support with said seat portion for folding movement toward and away from said seat portion, said intermediate support in its operative position serving as a bracing strut between said folding leg structures and also serving as a foot rest and shelf.

10. In a folding bathroom stool, the combination of a sheet-metal seat portion, said seat portion having centrally disposed drain apertures and top surfaces sloping toward said drain apertures, sheet-metal leg structures pivotally connected with said seat portion for sidewise folding movement into positions substantially parallel with the under side of said seat portion, a sheet-metal intermediate step, means pivotally connecting said intermediate step with said seat portion for fore and aft folding movement into a position closely adjacent the under side of said seat portion, said intermediate step having centrally disposed drain apertures and top surfaces sloping toward said drain apertures, and rubber feet on said leg structures having non-skid lower surfaces adapted to sit directly on the bottom surface of a bath tub.
